ABSTRACT OF THE DISCLOSURE

This disclosure relates to a machine for straightening rolled products which include a number of shafts on which straightening rollers are rotatably mounted, the shafts being received in sleeves which are axially adjustable through sleeves provided between the sleeves into the frame of the machine. The sleeves are rotated by power means through a gear train. The improvement comprises providing internal gear teeth on the free ends of the sleeves which mesh with pinions, the pinions being connected through a drive shaft through a power means and in which the power means comprises combined gear motor unit.

SUMMARY OF INVENTION

The invention concerns a roller straightening machine with axially adjustable straightening roller shafts which are supported in a bearing body in the shape of a hollow cylinder which, in turn, is supported in the machinery frame and by means of an external thread engages a corresponding female thread of the machinery frame. The axial adjustment of the straightening roller shaft is performed by a rotation of the bearing body executed with the aid of a power drive which rotates in the thread which guides it screws backward or forward, respectively, depending on the sense of rotation. In the known machines the transmission of the drive forces is performed via worm gears designed as reducing gears whose last worm wheel, in the direction of the drive, is provided on the free end of the bearing body. This well-known design shows a number of considerable disadvantages. One has reference to the fact that the shaft of the worm acting on the bearing surface must be arranged in the frame of the machine within the range of the bearing body crosswise to the longitudinal direction of the straightening roller shafts resulting in a relatively complicated construction and a considerable space requirement result for the drive arrangement. Beyond that, the worm gear participates in the axial adjustment so that the usual design fitting the worm can not be employed so that a simple gear rim arrangement with slanting teeth must be used. Such a gear rim permits, in each case, only small bearing surfaces so that high surface pressures result which adversely influence the lifetime and utilization of the gearing.

The present invention provides a drive similar in construction and service which with small dimensions permits avoiding unfavorable surface pressures.

The solution for this problem is found by equipping the bearing bodies of the roller straightening machine holding the straightening roller shafts with an internal gearing with which a prearranged geared motor meshes with the aid of a pinion provided on a drive shaft parallel to the axis. In doing this it has proved valuable to flange the motor to the frame of the machine. In the preferred arrangement the geared motor is equipped with a braking device which blocks it.

In detail the characteristics of the invention are explained with the aid of the following description of a practical example in conjunction with a drawing illustrating the latter.

5 The straightening roller shaft 1 is held in a bearing body 2 shaped as a hollow cylinder which, in turn, is supported in the machine frame 4 by means of a bushing 3. The bearing body 2 is equipped with an external thread within a portion 5, with which a corresponding internal thread 6 of the machine frame 4 meshes.

10 The free end of the bearing body 2 is equipped with an internal gearing 7 which is in operational contact with a pinion 8, the latter being arranged on the drive shaft 9 of a geared motor 10. The geared motor, whose plane of intersection lies so far behind that of the straightening roller shaft and that of the machinery parts supporting it, that the pinion meshes with the rim of the gear, is flanged to the wall 12 of the machinery frame via an opening. A shoulder of the flange 11 takes over in this 20 task of centering within the opening.

To carry out an axial adjustment the braking device, coordinated with the geared motor 10 feasibly within the gearing, is released and the motor is energized in the suitable sense. Geared down by the intermediate gearing, it drives the drive shaft 9 which rotates the bearing body 2 by means of the pinion 8 meshing with the rim of the gear 7. The threads 5 and 6 herein effect the desired axial adjustment.

30 The meshing of the pinion 8 with the gear rim 7 remains independent of the length of adjustment and within the whole adjustment region of the straightening roller shaft 1 usual values of the surface pressure are attained. In doing this it is only required to shape the pinion 8 in such a manner that its length exceeds the thickness of

35 the gear rim 7, at least by the length of adjustment of the straightening roller shaft. Simple spur gearing, slanting teeth gearing or the like may be used at will. This design of a roller straightening machine is not complicated by coordinating the drives effecting the axial adjustment

40 since these as preassembled motor and drive units represent only a comparatively small outlay and there is only a simple opening in the wall 12 of the machinery frame to be provided in conjunction with drilled holes for the support bolts to get them mounted. Also, if maintenance

45 or service work becomes necessary, the compact, simple design permits checking or dismantling at low cost. The design, compact in itself, proves space saving, especially due to the fact that the meshing of the drive of the bearing bushing is placed into the space required by itself due to the internal gearing. By avoiding unadvantageously small surfaces of application, one achieves that even with a relatively small diameter as well as a small thickness of the internal gearing 7, values of surface pressure can be 55 attained which do not exceed the usual values.

In accordance with the provisions of the patent statutes, I have explained the principle and operation of my invention and have illustrated and described what I consider to represent the best embodiment thereof. However,

60 I desire to have it understood that within the scope of the appended claims, the invention may be practiced otherwise than as specifically illustrated and described.

I claim:

65 1. In a roller straightening machine including a plurality of shafts each for carrying a straightening roller, an outer concentric sleeve for each shaft, said sleeves being supported for axial adjustment by a stationary frame, external threads being formed on each sleeve and arranged to mesh with separate internal threads formed 70 on said frame,

power means for each sleeve and including a gear train for rotating said sleeves relative to said frame, the improvement comprising free ends being formed in each sleeve on which ends are formed internal gear teeth, a pinion means for each sleeve arranged in meshing relationship with the internal gear teeth of the sleeves, means for connecting said pinion means to said power means, and each power means comprising a combined gear motor unit.

2. In a roller straightener according to claim 1 where-
in each gear motor unit includes a flange, and
means for securing said flanges to said frame.

3. In a roller straightener according to claim 1 where-
in said gear motor units each include a braking device.
